(57) **CLAIM**

The ornamental design for a pregnancy symbol, as shown and described.

DESCRIPTION

FIG. 1 is a front plan view of the pregnancy symbol.

FIG. 2 is a right side plan view of the pregnancy symbol.

FIG. 3 is a back plan view of the pregnancy symbol.

FIG. 4 is a left side plan view of the pregnancy symbol.

FIG. 5 is a top plan view of the pregnancy symbol; and,

FIG. 6 is a bottom plan view of the pregnancy symbol.

The disclosed embodiment can also be mirror imaged and the contour of the image may be flat or molded as long as the general outline of the symbol is the same.
